(57) **CLAIM**

The ornamental design for a light fitment, as shown and described.

DESCRIPTION

FIG. 1 is a front perspective view of a light fitment according to my new design;

FIG. 2 is a side view of the light fitment of FIG. 1;

FIG. 3 is a rear view of the light fitment of FIG. 1;

FIG. 4 is an underneath plan view of the light fitment of FIG. 1;

FIG. 5 is an underneath plan view with bracket in a first alternative position of the light fitment of FIG. 1;

FIG. 6 is an underneath plan view with bracket in a second alternative position of the light fitment of FIG. 1;

FIG. 7 is a front perspective view with lamp in an alternative position;

FIG. 8 is a rear view with mounting bracket removed of the light fitment of FIG. 1;

FIG. 9 is a front perspective view from above and one side of mounting bracket of the light fitment of FIG. 1;

FIG. 10 is a rear view of mounting bracket of the light fitment of FIG. 1; and,

FIG. 11 is a plan view of mounting bracket of the light fitment of FIG. 1.

The brackets are shown separately in FIGS. 9-11 for illustrative purposes only.
